UNITED STATES PATENT OFFICE.

ANDREW C. EDGAR, OF NEWTOWN SQUARE, PENNSYLVANIA.

STEAM AND HOT-WATER BOILER FURNACE.

1,261,370.

Specification of Letters Patent.

Patented Apr. 2, 1918.

Application filed March 8, 1917. Serial No. 153,350.

To all whom it may concern:

Be it known that I, ANDREW C. EDGAR, a citizen of the United States, and a resident of Newtown Square, county of Delaware, 5 State of Pennsylvania, have invented certain Improvements in Steam and Hot-Water Boiler Furnaces, of which the following is a specification.

My invention relates to boilers used for 10 heating buildings either with hot water or steam.

The invention relates particularly to boilers consisting of cast iron sections having portions extending over the fire.

15 One object of my invention is to construct a boiler furnace of this type in such a manner that the products of combustion will be thoroughly consumed before entering the chimney. The invention can be used either 20 for the burning of soft coal or of hard coal, as the case may be.

A further object of the invention is to locate a fire brick section above the fire in the combustion chamber.

25 A still further object of the invention is to provide means for supplying air to the upper part of the combustion chamber as fully described hereinafter, reference being had to the accompanying drawings, in which:

30 Figure 1 is a sectional elevation of a boiler furnace illustrating my invention and taken on the line 1—1, Fig. 2;

Fig. 2 is a sectional view on the line 2—2, Fig. 1;

35 Fig. 3 is a perspective view of one of the fire brick sections;

Fig. 4 is a view of a modification illustrating a type of boiler having cast iron sections with two depending legs;

40 Fig. 5 is a sectional view on the line 5—5, Fig. 4; and

Fig. 6 is a view of a modification of the means for admitting heated air to the combustion chamber from the ash pit.

45 1 is the base of the furnace. 2 is the grate, of any suitable type. 3, 3, are the intermediate cast metal boiler sections. 4 are the end sections of the boiler. These sections are made hollow, as shown, and communicate one with another so as to allow the water to circulate freely through all of the sections. Each of the intermediate sections 3 has a depending leg 5 at the rear in which is formed the mud drum 6. The side sections extend down to a point in a line with the legs and form with the intermediate sec-

tions the walls of the fire chamber. Each section is made with passages 7 and 8 forming, when two sections are placed side by side, flues for the escape of the products of combustion and depending from each of the intermediate sections, in the present instance, are tongues 9 which form flue passages of a greater area than the flues 7 and 8. These tongues project toward the fire 65 and are hollow and communicate with the legs. They also terminate short of the front plate of the furnace, as shown. The tongues are slightly inclined so as to allow sediment to flow into the back leg and into the mud 70 drum. Formed on the lower edge of each tongue is a double ledge 11 and formed on the under portion of the sections 4 are ledges 12. 13 are blocks of fire brick shaped as clearly shown in Fig. 3, and arranged to 75 fit snugly in the space between the tongues 9 and between the tongues and the end sections.

The ledges 11 and 12 extend into grooves in the sides of the fire bricks so that when the fire bricks are in position they extend under the tongues and protect them to a certain degree. The fire bricks fit close against the rear wall of the combustion chamber, and terminate short of the front of 80 the boiler furnace, as shown in Fig. 1, so as to leave a channel for the passage of the products of combustion into the flue 15 directly above the fire bricks.

By this construction the fire brick sections become hot as they are directly above the fire in the combustion chamber and as the gases pass up from the bed of fuel on the grate they are not fully consumed but, when they come in contact with the hot fire brick 95 sections and as they pass around said sections through the flue 15 to the flue 8 they become consumed so that comparatively little unconsumed gases escape to the chimney.

In order to aid in the combustion of the 100 unconsumed gases, I preferably form communication between the upper portion of the ash pit in the base 1 and the upper portion of the combustion chamber directly under the fire brick sections 13. In the present instance, I locate between the base 1 and the back leg of the boiler sections a box 19. The bottom of the box communicates through a series of passages 20 with the ash pit directly under the grate and through 105 passages 21 in each of the legs of the water sections of the boiler with the upper por-

tion of the combustion chamber directly under the firebricks 18. This passage 21 is greater in diameter at the bottom than at the top so as to prevent it from choking with soot or ashes. The box 19 has a detachable cover at each end so as to allow for the removal of ashes accumulating in the box. The air at the underside of the grate, which becomes heated, passes into the box 19 and 10 from the box through the channel 21 to the combustion chamber so that hot air is added to the unconsumed products of combustion as they pass in contact with the hot fire bricks and aids materially in the combustion of the said gases. In the front plate 15 of the furnace is the main fire door opening closed by a fire door 16. This fire door is made hollow, as shown, and the upper portion projects slightly into the combustion chamber. In the bottom of the fire door is a series of openings to admit air and in the upper portion is a series of openings which communicate with the combustion chamber so as to allow the air which becomes heated, 20 as it passes through the door, to enter the combustion chamber and also aid in the combustion of the gases.

17 is a clean out opening closed by a suitable door and 18 is another clean out opening for the flues 7 and 8.

While my invention is particularly adapted for cast iron sectional boilers of the type in which a part of the boiler overhangs the fire chamber, as illustrated in Figs. 1 35 and 2, the invention can be used in connection with a type of cast iron sectional boiler in which each section has two legs 5^a extending on each side of the fire chamber, as shown in Figs. 4 and 5. In this type of 40 boiler, ribs 14^a may be formed on the legs to support the fire brick sections 13^a and tongues may depend from the center of each section to support the fire bricks in the manner shown in Fig. 2, but, where the fire pot 45 is narrow, these tongues may be dispensed with and a single brick may extend from one side leg to the other.

Where the space between the surface of the grate and the fire bricks is limited, I 50 may construct the hot air box 19^a at the rear of the boiler sections, as illustrated in Fig. 6, and connect this box with the ash pit through one or more tubes 20^a and with the combustion chamber through passages 21^a in 55 the water section.

By making the sections of the boiler in the manner above described, the sections can be added according to the amount of heat desired and the sections of fire brick can 60 also be added, as required. The area of the flues is increased in proportion to the area of the heating surface and the grate surface. By locating the fire brick sections in the space between the depending tongues the fire 65 brick sections can be readily placed in posi-

tion and can be added as the number of sections of the boiler is increased, thus always insuring the proper relation between the grate surface and the fire brick sections, so that practically all of the unspent gases arising from the bed of fuel are consumed. In the event of one of the fire brick sections breaking, it can be readily removed through the opening 17 and another fire brick can be placed in position.

75 I claim:

1. The combination of a boiler consisting of a series of cast iron sections forming, when assembled, a combustion chamber and flues, with fire brick sections located in the upper portion of the combustion chamber and forming an additional flue so that when the fire brick sections become heated the heat will consume the unconsumed products of combustion escaping from the bed of fire.

2. The combination of a sectional boiler having intermediate and end sections, the intermediate sections having depending flanges, the end sections also having flanges forming ledges; and fire brick sections mounted on the flanges and forming the crown of the combustion chamber.

3. The combination in a sectional boiler furnace, of a grate; end boiler sections and intermediate sections extending over the grate, said sections having depending tongues flanged at the lower edge to form ledges; and fire brick sections mounted on the ledges and forming the crown of the combustion chamber.

4. The combination in a boiler of the cast metal sectional type, of a grate; a series of boiler sections consisting of intermediate hollow sections each having a depending leg extending over the grate and side sections, said side sections and intermediate sections forming the rear walls of the combustion chamber; flues partly in one section and partly in the other and communicating with the combustion chamber and with the flue leading to the chimney, the intermediate sections having depending tongues; ledges at the lower edges of the tongues; ledges at the inner portions of the side sections; fire brick sections mounted on the ledges, said fire 115 brick sections stopping short of the front of the furnace and forming the crown of the combustion chamber and a flue forming communication between the combustion chamber and the main flues of the boiler.

5. The combination of a sectional cast metal boiler having intermediate and end boiler sections; a grate over which the said sections extend; tongues on the intermediate sections, said tongues having ledges; fire 125 brick sections grooved at each edge and resting on the ledges and underlapping said ledges and forming the crown of the fire chamber.

6. The combination in a boiler furnace of

- the cast metal sectional type, of a base section forming an ash pit; a grate mounted on the base section; a series of boiler sections extending over the grate and forming the 5 back wall of the furnace; a box extending along the back of the furnace and between the grate and the boiler sections; means for conducting air from the ash pit to the box, the boiler sections having passages therein 10 communicating with the box and with the upper portion of the combustion chamber directly under the fire brick sections.
7. The combination in a boiler furnace of the cast metal sectional type, of intermediate 15 and side sections having depending legs forming the back of the combustion chamber; a base on which the sections of the
- boiler are mounted; a grate; a box located between the base and the depending legs of the boiler sections at the back of the fire 20 chamber, said box communicating with the ash pit, each of the intermediate sections of the boiler having tapered passages in the legs thereof forming communication with the box and the upper portion of the combustion chamber. 25
8. A section of a steam boiler furnace having portions extending over the grate and having a depending leg at the back, the leg having a passage therein open on its under side and open at its upper end near the portion extending over the grate. 30

In witness whereof I affix my signature.
ANDREW C. EDGAR.
